(57) **CLAIM**

The ornamental design for a multifunctional solar light, as shown and described.

DESCRIPTION

FIG. 1 is a perspective view of a multifunctional solar light showing my new design.

FIG. 2 is a front view thereof.

FIG. 3 is a rear view thereof.

FIG. 4 is a right end view thereof.

FIG. 5 is a left end view thereof.

FIG. 6 is a top view thereof; and,

FIG. 7 is a bottom view thereof.

The broken lines in the drawings represent unclaimed environmental subject matter that forms no part of the claimed design.
